CLAIM

The ornamental design for a misting and watering device, as shown and described.

DESCRIPTION

FIG. 1 is a front, right and top perspective view of a misting and watering device, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the misting and watering device thereof, shown in a position of extension;

FIG. 10 is a perspective view of the misting and watering device thereof, shown in a position of separation; and,

FIG. 11 is an enlarged detail view of portion 11 encircled in FIG. 2.

The broken lines shown in the drawings illustrate portions of the misting and watering device that form no part of the claimed design.

The dot-dash broken lines depict the boundaries of the enlargements that form no part of the claimed design.

1 Claim, 11 Drawing Sheets
